UNITED STATES PATENT OFFICE.

FRANCIS A. WEISBECKER, OF BROOKLYN, NEW YORK.

METAL-POLISHING MACHINE.

SPECIFICATION forming part of Letters Patent No. 733,099, dated July 7, 1903.

Application filed March 31, 1903. Serial No. 150,352. (No model.)

To all whom it may concern:

Be it known that I, FRANCIS A. WEISBECKER, a citizen of the United States, residing at Brooklyn, in the county of Kings and 5 State of New York, have invented certain new and useful Improvements in Metal-Polishing Machines, of which the following is a specification, such as will enable those skilled in the art to which it appertains to make and 10 use the same.

The object of this invention is to provide an improved machine for polishing sheet metal, and which is simple in construction and operation and comparatively inexpensive and 15 by means of which sheet metal of any kind or class may be quickly, easily, and conveniently polished at a comparatively light expense; and with these and other objects in view the invention consists in a machine of the 20 class and for the purpose specified constructed as hereinafter described and claimed.

The invention is fully disclosed in the following specification, of which the accompanying drawings form a part, in which the separate 25 parts of my improvement are designated by suitable reference characters in each of the views, and in which—

Figure 1 is a front view of my improved polishing-machine; Fig. 2, a section on the 30 line 2 2 of Fig. 1; Fig. 3, a section on the line 3 3 of Fig. 1, and Fig. 4 a section on the line 4 4 of Fig. 2.

In the practice of my invention I provide a strong and substantial frame, which in the 35 form of construction shown comprises end plates *a*, connected by cross-rods *a*², and this frame is preferably provided with a top cover *a*³, in which is mounted a shaft *b*, which passes therethrough and is provided at one 40 end with a tight belt-wheel *b*² and a loose belt-wheel *b*³ and which is also provided at the opposite end with a pulley or belt-wheel *b*⁴. Mounted on the shaft *b*, within the top portion *a*³ of the main frame of the machine, 45 is a roller *c*, which preferably consists of a central portion *c*², covered by lagging *c*³, of wood, over which is placed polishing material *c*⁴, which may consist of felt, fine brush material, or any other suitable substance usually 50 employed in polishing or buffing machines. Below the roller *c* is placed a transverse feed-shaft *d*, which passes through vertically-ar-

ranged slots or openings *d*² in the end members *a* of the main frame, and the ends of said shaft pass through vertically-movable bearings *d*³, mounted in said slots or openings, and the position of these bearings may be regulated vertically by means of regulating-screws *d*⁴, which pass through suitable supports *d*⁵ and are provided with heads or handles *d*⁶, by which they may be operated, and by means of this construction the shaft *d* may be adjusted vertically and with reference to the polishing-roller *c*. In front of and slightly below the shaft *d* is a supplemental brush-roller *e*, the shaft *e*² of which is movable in segmental slots *e*³ in the end members *a* of the main frame, and the ends of this shaft pass through arms *e*⁴, pivoted at the ends to the main frame at *e*⁵, and by raising and lowering the arms *e*⁴ the position of the brush-roller *e* may be adjusted with reference to the 65 position of the polishing-roller *c* and the shaft *d*, and the arms *e*⁴ are provided with set-screws or other suitable device *e*⁶, by which they 70 may be secured at any desired point of adjustment.

The frame-rod *a*², which is arranged in front of and slightly above the brush-roller *e*, is provided with spring-fingers *f*, having collars *f*², through which the said rod *a*² passes, and these collars are provided with set-screws *f*³, and said spring-fingers may thus be adjusted or raised and lowered as may be desired, and the operation thereof will be hereinafter explained.

The shaft *d*, the central portion of which serves as a feed-roller and is larger than the ends thereof, is also provided at one end with a drive-wheel *d*⁷, and the shaft *e*² of the brush-roller *e* is provided at one end with a pulley or belt-wheel *e*⁷, which is geared in connection with the pulley or belt-wheel *b*⁴ by a belt or other suitable device *g*, and in practice the machine is operated by means of the wheels *b*² and *d*⁷, which are geared in connection with a main power-shaft, which is not shown, or which may be geared in connection with any suitable power device.

In the bottom portion of the main frame is 105 mounted a receiver *h*, intended to receive the metal plates after they have been passed through the machine, and this receiver is preferably of the form shown in Figs. 2, 3,

and 4, being deeper at the front than at the rear thereof and being inclined downwardly and forwardly and being also supported by means of side plates h^2 , pivoted thereto and 5 provided with longitudinal slots h^3 , through which are passed bolts or screws h^4 , which are passed into the end portions a of the main frame, and by means of this construction the position of the receiver h may be regulated 10 and adjusted as desired.

In the operation of this machine the metal plates are fed through the machine in the direction of the arrow x in Fig. 1, the position of a plate being indicated by the dotted lines 15 x^2 , and in this operation the plates are passed over the spring-fingers f , over the brush-roller e , and between the feed-roller d and the polisher c . It will be understood, of course, that the shaft b and rollers c may be driven 20 at any desired speed, and with the construction shown the roller e or the shaft thereof will turn with the same speed as the shaft b . The feed-roller d may also be turned at any desired speed, but in practice is preferably 25 turned at a much lower speed than the polishing-roller c ; but it will be understood that the speed of the revolution of the brush-roller e , the polishing-roller c , and the feed-roller d may be regulated as desired.

30 In practice the brush-roller e serves to clean the bottom of the metal sheet and to partially polish the same as it passes through the machine, while the polishing-roller c operates to thoroughly polish the upper surface 35 of said sheet. After the sheet has passed through the machine or between the roller c and feed-roller d it drops into the receiver h and slides downwardly and forwardly and may be removed therefrom in any desired way.

40 The receiver h is also intended to contain a lacquer or other suitable polishing liquid, and after the sheet has been passed once through the machine it may be removed from the receiver h and again passed through the 45 machine, and in this operation it may be reversed, so as to polish both sides thereof.

The spring-fingers f may be adjusted so as to regulate the pressure of a sheet of metal on the roller e or so as to raise said sheet, and 50 thus present a greater portion of the upper surface thereof to the polishing-roller c , and it will be apparent that the polishing-roller c , the feed-roller d , and the brush-roller e may be driven in any desired manner.

55 My improved polishing-machine is simple in construction and operation and comparatively inexpensive and is not liable to get out of order or frequently need repair, and by means thereof sheets of metal of any kind

or class may be quickly polished either on 60 one or both sides.

Having fully described my invention, what I claim as new, and desire to secure by Letters Patent, is—

1. In a machine of the class described, a 65 frame, a polishing-roller mounted in the top portion thereof, a vertically-adjustable feed-roller mounted below the polishing-roller, and a brush-roller mounted below the polishing-roller and in front of the feed-roller and adjustable toward and from the polishing-roller, substantially as shown and described. 70

2. In a machine of the class described, a frame, a polishing-roller mounted in the top portion thereof, a vertically-adjustable feed-roller mounted below the polishing-roller, and a brush-roller mounted below the polishing-roller and in front of the feed-roller and adjustable toward and from the polishing-roller, and a rod passing transversely through the 80 frame in front of the brush-roller and provided with backwardly-directed spring-fingers which are vertically adjustable, substantially as shown and described. 75

3. In a machine of the class described, a 85 frame, a polishing-roller mounted in the top portion thereof, a feed-roller mounted below the polishing-roller, a brush-roller mounted below the polishing-roller and in front of the feed-roller, a rod or support passing transversely 90 through the frame in front of the brush-roller and a receiver mounted in the frame below said rollers and extending upwardly and rearwardly of the frame, substantially as shown and described. 95

4. In a machine of the class described, a frame, a polishing-roller mounted in the top portion thereof and vertically-adjustable feed-roller mounted beneath the polishing-roller, a brush-roller mounted in front of the feed-roller and below the polishing-roller, a frame-rod arranged in front of the brush-roller and parallel therewith and provided with vertically-adjustable fingers and an adjustable receiver mounted in the bottom portion of the frame 100 and held in an upwardly and backwardly position and adapted to receive sheets of metal after they have passed through the machine, substantially as shown and described. 105

In testimony that I claim the foregoing as 110 my invention I have signed my name, in presence of the subscribing witnesses, this 20th day of February, 1903.

FRANCIS A. WEISBECKER.
